UNITED STATES PATENT OFFICE.

CHRISTOPHER C. SHELBY, OF PATERSON, NEW JERSEY.

BUSTLE.

SPECIFICATION forming part of Letters Patent No. 374,632, dated December 13, 1887.

Application filed October 15, 1887. Serial No. 252,468. (No model.)

To all whom it may concern:

Be it known that I, CHRISTOPHER C. SHELBY, of Paterson, in the county of Passaic and State of New Jersey, have invented certain new and useful Improvements in Bustles; and I do hereby declare the following to be a full, clear, and exact description of the same, reference being had to the accompanying drawings, forming a part of this specification, and to the figures 10 and letters of reference marked thereon.

The present invention relates to certain improvements in that class of bustles employing a series of hoop-reeds for distending the overhanging dress, adapted to be collapsed or 15 swung upward against the person when pressure is brought to bear upon them—as, for instance, when the wearer is seated.

It has for its object to provide an efficient means for opening the collapsed ribs; and to 20 this end it consists in an improved spring, as will be hereinafter described, and pointed out particularly in the claims at the end of this specification.

In the accompanying drawings, Figure 1 is 25 a perspective view of a bustle constructed in accordance with my invention. Fig. 2 is a similar view showing the spring applied to the inside. Fig. 3 shows the bustle in collapsed position.

30 Similar letters of reference in the several figures indicate the same parts.

In the form of bustle shown in the drawings the hoop-reeds A are hinged to the main reed B, their downward movement being limited 35 by the strap or flexible connection C, connecting the center of each of the bows to the top of the main reed. The width of the bustle may be adjusted by the lacing connecting the ends of the main reed, which is preferably of 40 spring material, in order that the tendency of the ends may be to separate and keep the lacing taut. Hinged, preferably, to the lower hoop-reed is a long spring bow or reed, D, passing up outside of the hoop-reeds A, as 45 shown in Fig. 1, or else inside the same, as shown in Fig. 2, the center of the bow being also connected to the strap C, usually at about the same distance from the main reed as the distance between them at the bottom. At 50 about midway between the ends and the top of bow D the two ends are connected together

1 by lacing E, which, in order to give more play to the spring, is preferably elastic, although this, as will be readily seen, is not absolutely essential. The center of the bow, besides being connected to the strap C, is held down at this point by a lacing, F, connecting it with the main reed at each side. 55

In use, when the hoop-reeds are collapsed, as before mentioned, the spring-reed D will be 60 forced up at either side into bows b, (shown in Fig. 3,) and in this position the said bows b will bear a portion of the superimposed dress, which, when the pressure is relieved, will assist in returning the bustle to proper or open 65 position, the spring forcing the bottom hoop-reed down, and it, being connected to the others by strap C, draws them down also.

While I have shown the spring D as made of metal similar to the hoop-reeds, as held 70 down at the center by lacing designed especially for the purpose, and as connected to the flexible strap C at a particular distance from the main reed, I do not wish to be limited to these identical features, as it is obvious that 75 they may be varied considerably without departing from the spirit of my invention. For instance, the spring may be made of other material than metal and the lacing connecting its center with the main reed at the sides 80 may be entirely done away with, the strap C being relied on to hold it down at this point; or it may be connected directly to the main reed at the center.

Having thus described my invention, what 85 I claim as new is—

1. In a bustle, the combination, with the main reed and series of flexibly-connected collapsible hoop-reeds hinged to the main reed, of a spring connected to one of said hoop-reeds 90 at each side and extending upward in a bow, said spring being centrally connected to the main reed to prevent its expansion at the center, its sides being free to expand when the hoop-reeds are collapsed, substantially as described. 95

2. In a bustle, the combination, with the main or supporting reed and series of flexibly-connected collapsible hoop-reeds hinged to the main reed, of a spring connected to one of said 100 hoop-reeds at each side and extended upward in a bow, which is centrally connected to the

main reed to prevent its expansion at the center, its sides being free to expand when the hoop-reeds are collapsed, and a lacing connecting the sides of said spring, substantially as described.

3. In a bustle, the combination, with the main or supporting reed and series of flexibly-connected collapsible hoop-reeds hinged to the main reed, of a spring connected to one of said hoop-reeds at each side and extended upward in a bow, which is centrally connected to the main reed to prevent its expansion at the center, its sides being free to expand when the hoop-reeds are collapsed, and an elastic lacing connecting the sides of said spring, substantially as described.

4. In a bustle, the combination, with the series of flexibly-connected collapsible hoop-reeds and main reed, to which they are hinged,

of a spring connected to one of said hoop-reeds, extended upward in a bow, and lacing connecting the center of said bow to the main reed at each side, substantially as described.

5. In a bustle, the combination, with the main reed and series of flexibly-connected collapsible hoop-reeds hinged to the main reed, of a spring connected to the outside of one of said hoop-reeds and extending upward in a bow, lacing connecting the center of said bow and the main reed for preventing the expansion of the center of said bow, and lacing connecting its sides, substantially as described.
